SUPERCHARGER FUEL INJECTION

Kenneth A. Browne, Ridgewood, N. J., assignor
to Wright Aeronautical Corporation, a corpora-
tion of New York

Application November 6, 1943, Serial No. 509,316

7 Claims. (Cl. 261—90)

This invention relates to means for uniformly distributing the fuel supply to an internal combustion engine and is particularly directed to internal combustion engines equipped with superchargers.

It is an object of this invention to provide means for uniformly and symmetrically discharging the fuel into the airstream in front of the supercharger impeller. Unless some means are provided to maintain the pressure in the fuel passage up to the point of discharge of the fuel into the airstream, the low pressure at the entrance to the supercharger impeller will cause evaporation or boiling of the fuel with consequent uneven discharge of the fuel into the airstream. The symmetry of discharge from a constant area annular slot or a plurality of circumferentially disposed fixed holes from a fuel supply annulus is subject to gravitational effects, dynamic pressure effects in the fuel channel leading to the discharge points, and local variations in the static pressure of the air passing into the supercharger. The magnitude of these factors effecting non-symmetry of fuel distribution are inversely proportional to the pressure drop across the fuel discharge orifice. Due to the operating range covering a 5 to 1 variation in fuel flow, the pressure drop across a fixed area fuel discharge orifice varies 25 to 1 for the above fuel flow variation. This results in excessive pressure requirements at the highest flow, when adequate fuel pressure drop across the discharge orifice to provide symmetrical discharge of fuel is provided at the lowest usable fuel flow. Accordingly, it is an object of this invention to locate a fuel pressure control valve directly at the point of discharge of the fuel into the airstream.

Other objects of this invention will become apparent upon reading the annexed detailed description in connection with the drawing in which:

Fig. 1 is an axial section of a supercharger embodying the invention.

Fig. 2 is a section on line 2—2 of Fig. 1, and

Fig. 3 is an axial section through a modification.

Referring first to Figs. 1 and 2, a supercharger impeller 10 is mounted within a portion of the engine casing 12 and is provided with an air intake duct 14, the rear wall of which is illustrated at 16. The air duct 14 delivers air from a carburetor or other fuel-air proportioning device shown diagrammatically at 17 to the impeller annular intake opening between the impeller hub 13 and shroud 15. The impeller 10

compresses and delivers the combustible mixture to an intake manifold from whence it is distributed to the various engine cylinders. The impeller 10 is drivably splined to the shaft 18, driven by the internal combustion engine. The impeller drive shaft 18 extends through an opening in the rear wall 16 of the air duct and an oil seal sleeve 20 is carried by the impeller shaft in cooperation with a bushing member 22 secured to the rear wall of the intake duct 14. The structure so far described is quite conventional, e. g., as more fully illustrated in the copending application, Serial No. 463,559 of F. Wiegand.

A fuel passage 24 extends through the rear wall 16 from the fuel-air proportioning means and terminates in an annular chamber 26 immediately in front of the supercharger impeller and concentric therewith. An annular collar 28 is secured across and closes the impeller end of this chamber and is provided with a plurality of uniform and circumferentially disposed valve port slots or openings 30. The number of such openings is not important but for symmetry seven or fourteen, e. g., are preferable in a fourteen-cylinder engine. A rotatable collar or valve member 32 is disposed in front of the collar 28 and urged thereagainst by an annular spring member disposed between the valve member 32 and a nut 34. The valve member 32 is provided with a number of circumferentially spaced V-shaped notches 36 corresponding in number and spacing to valve port openings 30 and cooperable therewith.

As best seen in Fig. 2, each of the valve ports 30 is elongated in a direction substantially 45° to a radial direction, and one edge of the associated notch 36 is disposed substantially at right angles to the longitudinal dimension of the valve port. Obviously this arrangement of the valve ports 30 and notches 36 is not critical; it is only essential that the notches be adapted to control the size of the valve opening. Thus, one edge of each of the notches 36 is adapted to cover or uncover more or less of the associated valve port 30 upon rotation of the valve member 32. A radially extending arm 38 is secured to the valve member for operation of the valve. A double ended piston member 40, slidably disposed within a cylinder, is provided with a transverse projection 42 extending through an elongated slot in the cylinder and adapted to be straddled by the forked end 44 of the arm 38. In this way movements of the piston 40 are operable through the arm 38 to rotatably adjust the valve member 32. One end of the piston is subjected to

fuel pressure transmitted by passage 46 from the annular fuel chamber 26. The fuel pressure acts against one end of the piston 40 for urging the valve in an opening direction against a spring 48 acting against the other end of the piston. The latter end of the piston is vented through the passage 50, either to the atmosphere or to the Venturi suction in the airstream of a conventional fuel-air proportioning means. The design is such that the fuel pressure differential between full open and full closed positions of the valve member 32 is quite small, whereby a substantially constant fuel pressure is maintained on the upstream side of the valve. Furthermore, with the vent 50 connected to the Venturi suction in the airstream, the pressure on the vent side of the piston decreases with an increase in the magnitude of the fuel flow, thereby helping to maintain a substantially constant fuel pressure on the upstream side of the valve member 32. Also, the fuel discharge valve 32 of the present invention may comprise the fuel discharge valve of the fuel-air proportioning mechanism disclosed in applicant's prior Patent No. 2,165,-447. In this prior patent the end of a tubular member 34 operates as a fuel discharge valve under the control of a flexible diaphragm 31 urged by a spring 38 in a valve closing direction, the one side of this diaphragm being subjected to fuel discharge pressure for opening the valve while the other side of this diaphragm is connected to a chamber 32 subjected to a substantially constant pressure as the atmosphere. In other words, when used with the fuel-air proportioning device of this prior patent, the herein disclosed fuel passage 24 is connected to fuel passage 29 of the prior patent, and the flexible diaphragm 31 and associated valve of the prior patent are replaced by the herein disclosed movable piston 40 and its associated valve.

With the above construction the valve member 32 is located directly at the point of discharge of the fuel into the airstream and immediately in front of the supercharger impeller. The valve member 32 automatically operates to maintain the desired reasonably constant pressure on its upstream side and the uniformly spaced valve ports are operable to effect a symmetrical discharge of the fuel into the impeller airstream. Thus, upon an increase in the fuel pressure in the annular chamber 26, the piston 40 operates to adjust the valve member 32 in an opening direction to relieve this increase in fuel pressure and vice versa.

Fig. 3 illustrates a modification which generally is similar to Fig. 1 except for the structure of the fuel regulating valve and, in addition, the oil seal sleeve 61 is provided with an outwardly inclined flange 60 to help deflect the fuel discharged by the valve into the airstream in front of the impeller 62, as will be clear from the following description: An annular cap member 64 is secured to the rear wall 66 of the air intake duct 68 to form an annular chamber 70 at the end of the fuel passage 72 immediately in front of the impeller 62. The impeller end of the cap member 64 is concentrically disposed about the oil seal sleeve member 61 and in clearance relation thereto. An annular valve member 76 is slidably mounted on the bushing 78 and at its other end engages the interior of the cap member 64. As illustrated in Fig. 3, the interior surface of the cap member 64 is inclined relative to the valve member 76 such that movement of the valve member to the right in Fig. 3 uncovers

valve port means between these members for discharging fuel therethrough against the inclined flange 60 and thence into the airstream. The cap member 64 is provided with a plurality of circumferentially disposed grooves or recesses 86 comprising valve ports adapted to be uncovered by movement of the valve member 76 to the right. A spring 82 urges the valve member in a closing direction and a flexible diaphragm 84 secured to the valve member is subjected to the fuel pressure for opening the valve. The other side of the diaphragm is vented through passage 86 to the atmosphere or to the Venturi suction in the airstream of the conventional fuel-air proportioning means. The valve member 76, like valve member 32, thereupon is automatically operable by the fuel pressure to maintain a substantially constant fuel pressure on its upstream side. Also, the valve 76 may be used in connection with the fuel-air proportioning means disclosed in applicant's aforementioned prior patent as discussed in connection with Fig. 1.

In either of the above modifications a valve is disposed at the point of discharge of the fuel into the airstream immediately in front of the impeller for discharging fuel in a symmetrical pattern into the airstream and this valve is automatically operable to maintain the fuel pressure on its upstream side. Thus, both modifications illustrate a relatively simple arrangement for effecting uniform distribution of the fuel into the airstream.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. In a fuel distributing system for an internal combustion engine equipped with a supercharger impeller having a hub portion and an annular intake opening about said hub portion, a fuel passage terminating adjacent to the intake end of said impeller in valve port means, the downstream side of said valve port means being in substantially unrestricted communication with the impeller intake airstream, said port means being symmetrically disposed about the impeller axis whereby the fuel discharges through said port means symmetrically into the impeller intake airstream at said annular impeller intake opening, a member movable to effect opening and closing adjustments of said port means, and means responsive to the fuel pressure upstream of said valve port means for automatically moving said member in a direction to effect an opening adjustment of said valve port means in response to an increase in said fuel pressure and vice versa.

2. In a fuel distributing system for an internal combustion engine equipped with a supercharger impeller having a hub portion and an annular intake opening about said hub portion, a fuel chamber to which fuel is supplied under pressure and having valve port means opening substantially directly into the impeller airstream, said chamber being surrounded by the impeller intake airstream and disposed adjacent to the intake end of the impeller hub, said valve port means being so disposed about the impeller axis that the fuel discharges therethrough symmetrically into the impeller intake airstream at said

annular intake opening, a member movable to effect opening and closing adjustments of said valve port means, and means responsive to the fuel pressure upstream of said valve port means for automatically moving said member to effect a valve-port-opening adjustment in response to an increase in fuel pressure and vice versa.

3. In an internal combustion engine, an annular supercharger impeller, an impeller drive shaft, said impeller having an annular air intake opening about said shaft, an annular fuel chamber disposed about said shaft adjacent to the entrance end of said impeller, said fuel chamber having valve port means symmetrically disposed about said shaft and opening substantially directly into the impeller airstream whereby fuel discharges through said port means symmetrically into said airstream at said annular intake opening, a member movable to effect opening and closing adjustments of said port means, and means automatically operative to adjust said member in a direction to effect an opening adjustment of said valve port means in response to an increase in fuel pressure on the upstream side of said valve port means side and vice versa.

4. In a fuel distributing system for an internal combustion engine equipped with a supercharger impeller having a hub portion and an annular intake opening about said hub portion, a fuel chamber to which fuel is supplied under pressure disposed adjacent to the intake end of said impeller hub so as to be surrounded by the impeller airstream, said chamber having a plurality of valve ports opening substantially directly into the impeller airstream, and circumferentially spaced about the impeller axis adjacent the impeller so that fuel discharges through said ports symmetrically into the surrounding impeller intake airstream at said annular intake opening, a member rotatable to effect opening and closing adjustments of said valve ports, said member having an arm projecting radially therefrom, and means operatively engaging said arm and responsive to the fuel pressure upstream of said member for automatically moving said member to effect an opening adjustment of said valve ports in response to an increase in fuel pressure and vice versa.

5. In a fuel distributing system for an internal combustion engine equipped with a supercharger impeller having a hub portion and an annular intake opening about said hub portion, a fuel chamber to which fuel is supplied under pressure disposed adjacent to the intake end of said impeller hub so as to be surrounded by the impeller airstream, said chamber having a plurality of

valve ports with their downstream ends in substantially unrestricted communication with the airstream adjacent the impeller, said valve ports being circumferentially spaced about the impeller axis so that fuel discharges therethrough symmetrically into the surrounding impeller intake airstream at said annular intake opening, a member rotatable about the axis of said impeller for controlling said valve ports, and means responsive to the fuel pressure upstream of the member for automatically rotating said member in one direction to effect an opening adjustment of said valve ports in response to an increase in fuel pressure and vice versa.

6. In a fuel distributing system for an internal combustion engine equipped with a supercharger impeller having a hub portion and an annular intake opening about said hub portion, a fuel passage terminating adjacent to the intake end of said impeller in valve port means opening substantially directly into the impeller intake airstream, said port means being symmetrically disposed about the impeller axis whereby the fuel discharges through said port means symmetrically into the impeller intake airstream at said annular impeller intake opening, a member rotatable about the axis of said impeller to effect opening and closing adjustments of said port means, and means responsive to the fuel pressure upstream of said member for automatically rotating said member in a direction to effect an opening adjustment of said valve port means in response to an increase in said fuel pressure and vice versa.

7. In a fuel distributing system for an internal combustion engine equipped with a supercharger impeller having a hub portion and an annular intake opening about said hub portion, a fuel passage terminating adjacent to the intake end of said impeller in valve port means opening substantially directly into the impeller intake air stream, said port means being symmetrically disposed about the impeller axis whereby the fuel discharges through said port means symmetrically into the impeller intake air stream at said annular impeller intake opening, a member coaxial with said impeller axis and axially movable to effect opening and closing adjustments of said port means, and means responsive to the fuel pressure upstream of said member for automatically axially moving said member in a direction to effect an opening adjustment of said valve port means in response to an increase in said fuel pressure and vice versa.

8. In a fuel distributing system for an internal combustion engine equipped with a supercharger impeller having a hub portion and an annular intake opening about said hub portion, a fuel passage terminating adjacent to the intake end of said impeller in valve port means opening substantially directly into the impeller intake air stream, said port means being symmetrically disposed about the impeller axis whereby the fuel discharges through said port means symmetrically into the impeller intake air stream at said annular impeller intake opening, a member coaxial with said impeller axis and axially movable to effect opening and closing adjustments of said port means, and means responsive to the fuel pressure upstream of said member for automatically axially moving said member in a direction to effect an opening adjustment of said valve port means in response to an increase in said fuel pressure and vice versa.
